Filed July 11, 1960, Ser. No. 42,171

6 Claims. (Cl. 16—66)

This invention relates to improvements in a door closer, and is a continuation-in-part of application Serial No. 723,559, filed March 24, 1958, and now abandoned.

In door closers employing a coacting cylinder and piston construction and cooperating spring means therefore, it is usual to apply to the piston rod a specially formed washer-like element generally known as a "hold-open" washer which is slidably mounted on the piston rod and provided with an offset portion designed to engage that end of the cylinder through which the piston projects as to cause the washer to cant when it receives pressure exerted by the end of the cylinder, thus to bite against the piston rod and therefore when the piston rod has been withdrawn from the cylinder to a desired degree, making it possible to hold the door open. While this is a very desirable arrangement so as to give the user the option of maintaining the door open by means of a very simple operation, it has distinct disadvantages because due to the fact that the piston rod is cylindrical in character and the orifice in the washer is circular to conform therewith, the washer is rotatable on the rod. The biting of the washer into the rod causes nicks in the rod and moreover due to the fact that the washer is rotatable on the rod, nicks will be made at different places on the rod and throughout its circumference as the washer is used from time to time to maintain the door closing mechanism in open position. Accordingly, the burred portions of these nicks will engage the edges of the opening in the end of the cylinder through which the piston rod passes with the result that the door closer becomes subject to noisy chatter due to nicks in the rod which tend to engage the edge or edges of the orifice in the end of the cylinder and interfere momentarily with the smooth free passage of the rod through said orifice and which results in intermittently restrained movement.

The present invention avoids these disadvantages while maintaining the simple principle of locking the door closer in open position by means of a washer which is similarly canted to bite into the piston rod and functions in a substantially similar manner.

The invention generally comprises the combination, in a door closer having a cylinder, a piston therefor including a piston rod adapted to project from an orifice in one end of the cylinder and coacting spring means, of a hold-open washer slidably mounted on said piston rod having means engageable with said end of said cylinder when positioned adjacent thereto for causing said washer to cant into biting engagement with said rod whereby to prevent relative movement between said rod and cylinder, a means for retaining said washer from rotation on said rod whereby to cause said washer always to cant identically for each desired biting engagement along the length of the rod and to cause such engagement always along a predetermined identical path on said rod, said orifice of said cylinder being enlarged in registry with said path to avoid engagement with roughened areas on said rod along said path caused by the biting engagement of said washer. Preferably the piston rod is formed with opposed flat sides and the surface of the other two sides joining them are curved on a radius and form the predetermined identical path for biting engagement with said washer although it is obvious that other forms of rod could be used to achieve the desired result.

The invention will be fully described in the following

2

detailed specification taken in conjunction with the accompanying drawings which form part of the same.

In the drawings:

FIG. 1 is a top plan view of a door closer, embodying my invention, in mounted position between a door frame and a door, the door being illustrated fragmentarily and the frame sectionally.

FIG. 2 is a section taken through the piston rod adjacent to one end of the cylinder and illustrating the enlargement of the opening in the end of the cylinder through which the piston rod projects.

FIG. 3 is a perspective view of the hold-open washer employed in conjunction with the construction illustrated.

FIG. 4 is a perspective view of the end of the cylinder through which the piston rod projects showing the manner in which the hold-open washer is caused to bite into the rod to restrain the rod and cylinder from relative movement; and

FIG. 5 is a cross-section taken through an alternative form of piston rod rectangular in cross-section and showing a type of washer which may be employed in conjunction therewith for moving into biting engagement with such rod along a predetermined path.

FIG. 6 is an enlarged fragmentary perspective exploded view of one end of the cylinder of a door closer incorporating a dished end for the cylinder, a specially orificed bushing for receiving and guiding the rod and a washer for taking the end thrust of the spring; and

FIG. 7 is a fragmentary longitudinal section taken through the free end of the cylinder showing the parts of FIG. 6 in assembly.

Referring to the drawings, A indicates a door closer according to the present invention, as a whole, which is shown mounted between the door B and door frame C. The door closer is of generally conventional construction which employs a cylinder 10 enclosing a piston having its piston rod 11 projecting from one end of the cylinder and it includes within the cylinder spring means coacting with the piston and cylinder to cause a door to close. The cylinder is fastened to the door by a conventional bracket 12 pivotally connected to a bracket head 13 on one end of the cylinder and the piston rod is placed in operative connection with the door from C by a suitable bracket 14 to which the free end of the piston rod 11 is pivotally connected. The unit also includes a hold-open washer 15 which is offset at 16 and 17 as a means for causing the washer to cant when positioned adjacent to the end 18 of the cylinder 10 to engage the piston rod 11 in biting engagement and restrain it from movement farther into the cylinder 10, when it is caused to project to a predetermined degree from the cylinder.

According to the present invention a means is provided for restraining the hold-open washer from rotating on the piston rod 11 and this is preferably achieved by forming the piston rod with flat sides 19 and forming the hold-open washer 15 with a rectangular orifice 20 capable of receiving the piston rod in a manner to permit the hold-open washer slidably to move thereon, the opposed sides of the orifice 20 being designed to register with the flat sides of the piston rod as to prevent the washer from rotating on the rod. The opposite sides of the piston rod are preferably curved on a radius as indicated at 21 such that the edges 22 and 23 of the washer will be caused to bite the crown of the radius of the curved sides of the rod when the washer is caused to cant such as in the manner shown in FIGS. 1 and 4, thereby to prevent relative movement between the rod and the cylinder. Thus, biting engagement between the rod and the hold-open washer occurs always along a predetermined path, i.e. the curved sides of the piston rod, by reason of the fact that the washer cannot rotate. The orifice in the closure for the end 18 of the cylinder

through which the piston rod 11 is caused to project is formed with enlargements 24 intermediate opposed edges thereof and which are disposed in registry with a portion of the curved sides of the piston rod 11 or, in other words, in registry with the predetermined identical path of biting engagement between the washer and rod along the length of the latter. Such enlargements create shoulders on each side thereof for engagement with said rod on each side of said path as for the normal axial slideable guidance of said rod. Therefore, burred or nicked areas or locations on the rod along said path will not tend to engage the end closure of the cylinder at the edge of the orifice therein which normally has been the case with a cylindrical rod passing through an orifice of circular character as previously employed in the prior art. In this case, the enlargements 24 in registry with the path along the length of the rod where biting engagement takes place between the rod and washer provide a clearance between the rod and end closure of the cylinder such that nicked or burred parts of the rod pass the orifice freely and without engagement with edges thereof. Therefore, such burred, nicked or deformed portions of the rod will not, as in the past, cause the door closer to become noisy and subject to chatter due to nicks in the rod intermittently engaging the edge or edges of the orifice in the end of the cylinder and which would interrupt, momentarily, the smooth free passage of the rod through said orifice. Moreover, when employing the flat sided rod with opposite sides curved on a radius, the crown of the radius provides a narrow path along the length of the rod for biting engagement such that the enlargements 24 in the end orifice of the cylinder need not be of substantial extent.

While the above construction is the preferred form of construction, it is obvious of course that a structure of rod and washer might be formed otherwise as to attain the same objective. For instance, the rod might be formed rectangular in cross-section, as indicated in FIG. 5 at 25, in which case it is desirable to form the washer with the tongues 26 projecting into the orifice 27 thereof for biting engagement with the rod 25 along a predetermined path within the cross-sectional confines of the rod. The enlargements 24 of the end closure of the cylinder 10 would therefore in effect register with the tongues 26 of the washer. Likewise, other structures might be employed to prevent the rotation of the hold open washer and achieve the results of the present invention in the manner set forth.

In some instances when the free end of the piston rod is rotated by the installer to line it up with the bracket to which it is to be attached, the internal spring of the door closer pressing on the end of an orificed dished washer element closing the end of the cylinder, if such is employed, sometimes causes the washer to resist a corresponding turning movement, thus tending to cause the rod to bind at the opposite top and/or bottom corners of the orifice through which the rod projects from the cylinder. Alternatively, due to the constant compression and expansion of the spring and the tendency of the end of the spring to rotatably retreat or rotatably advance when compressed, this will sometimes cause an end closure washer where employed to rotate slightly as to cause the same effect, the end of the spring having a sharp edge which tends to dig into the washer since it is of softer steel than the spring. While this occurs infrequently and, therefore, the structure described in connection with FIGS. 1 to 5 is on the average very practical, even this infrequent occurrence can be avoided by the combination illustrated in FIGS. 6 and 7.

Here the cylinder 10, formed with the enlarged opening 28 achieved by turning in the ends of the cylinder to form the inwardly directed circumferential flange 29, is closed by a dished washer 30 having a central orifice 31 in its dished portion which portion is designed to receive a bushing 32 of suitable material such as nylon, formed

with orifice 33 through which the free end of the piston rod 11 projects. The bushing 32 is held in position within the dished portion of the washer 30 by means of a thrust washer 34 which assumes the thrust of the spring 35 disposed within the cylinder of the door closer.

The orifice 33 in the bushing 32 is formed identically with that illustrated in FIG. 2 whereby the orifice 33 of the bushing is provided with the diametrically opposed enlargements 36 disposed in registry with the path along the length of the rod where the biting engagement takes place between the rod and the hold-open washer 37. Consequently, when the piston rod 11 is rotated slightly to align the flat end thereof with the attached bracket to which it is anchored, the bushing 32 will turn with it even though such rotational movement may tend to be resisted by the engagement of the end of the spring 35 with the washer 34. In result, therefore, there is no tendency towards binding between the edges of the orifice 33 of the bushing 32 and the piston rod 11, whereas the enlargements 36 of the orifice located in registry with the path along the length of the rod where biting engagement takes place between the rod and the hold-open washer provide for exactly the same advantage previously described to eliminate any tendency of binding and resulting chatter between the opposed curved pistons of the rod burred by the hold-open washer and the edges of the orifice 33 axially aligned therewith, since such burred portions are clearly straddled by the enlargements 36 of the orifice 33. Though this construction is slightly more costly than that disclosed in FIGS. 1 to 5, it may be preferred.

It is clear from the foregoing that the present invention in a simple manner and with substantially no increase in cost or steps in construction avoids a deteriorating disadvantage which has been present in this general type of door closer construction used in the past.

What I claim as my invention is:

1. In a door closer, the combination of a cylinder, a piston within said cylinder including a piston rod adapted to project from a guiding orifice in one end of the cylinder and axially slideable back and forth through said guiding orifice, a hold-open washer slidably mounted on said piston rod having means engageable with said end of said cylinder, when positioned adjacent thereto, for causing said washer to cant into biting engagement with said rod whereby to restrain relative axial movement between said rod and cylinder, means for restraining said washer from rotation on said rod whereby to cause said washer to cant, for each desired biting engagement along the length of the rod, and cause such engagement always along a predetermined axially extending path on directly opposed surfaces of said rod, said guiding orifice having four sides and being enlarged on two directly opposed sides thereof, in an area intermediate the other opposed sides and in registry with said path, to avoid engagement of edges of said guiding orifice with roughened sections of said rod along said path caused by said biting engagement of said washer, said enlargements forming shoulders along edges of said guiding orifice for sliding engagement with said rod on each side thereof along said path for guiding said rod during its axial sliding movement.

2. The combination as claimed in claim 1 in which said directly opposed surfaces of the piston rod are transversely, outwardly curved whereby biting engagement between said washer and said rod occurs on the crown of said curved surfaces.

3. The combination as claimed in claim 1 in which the means for restraining said washer from rotation includes a pair of opposed flattened sides on the rod, said washer being formed with an orifice having straight side edges capable of engaging the flat sides of the rod to prevent rotation of the washer, the two remaining sides of said rod being curved on a radius and forming the predetermined path on said rod for biting engagement with said washer.

4. The combination as claimed in claim 1 in which the end of the cylinder through which the piston rod projects is substantially closed by a dished, centrally open washer, said dished washer rotatably carrying a bushing, the orifice of said bushing constituting said guiding orifice through which the piston rod projects.

5. In a door closer, the combination of a cylinder, a piston within said cylinder including a piston rod having a free end projecting from one end of the cylinder through a guiding orifice and being axially slideable back and forth through said guiding orifice, a rotatably mounted bushing carried in said end of said cylinder, the bushing passage constituting said guiding orifice for the piston rod, a hold-open washer slidably mounted on said piston rod having means engageable with said end of said cylinder when positioned adjacent thereto, for causing said washer to cant into biting engagement with said rod whereby to restrain relative axial movement between said rod and cylinder, means for restraining said washer from rotation on said rod whereby to cause said washer to cant, for each desired biting engagement along the length of the

rod, and cause such biting engagement always along a predetermined axially extending path on directly opposed surfaces of said rod, said guiding orifice having four sides and being enlarged on two directly opposed sides thereof, in an area intermediate the other opposed sides and in registry with said path, to avoid engagement of edges of said orifice with roughened sections on said rod along said path caused by the biting engagement of said hold-open washer, said enlargements forming shoulders along the edges of said guiding orifice for sliding engagement with said rod on each side thereof along said path, for guiding said rod during its axial sliding movement.

6. The combination as claimed in claim 5 in which a thrust absorbing washer is included in said cylinder inwardly of and in rotatable bearing engagement with said bushing.
